[57] ABSTRACT

The front end of a pipe cleaning nozzle body has a plurality of peripherally spaced fluid pressure jet ports therethrough arranged on axes which converge forwardly about a forwardly projecting tip to provide fluid pressure jets for dislodging solids accumulations in the pipe. Additional fluid pressure jet ports extend outward through the side of the body on axes which diverge angularly rearward to provide fluid pressure jets which assist forward movement of the nozzle and rearward expulsion of solids removed from the pipe.

PIPE CLEANING NOZZLE

BACKGROUND OF THE INVENTION

This invention relates to nozzles for removing solids accumulations from pipes by high velocity fluid jets, and more particularly to a nozzle of the class described having a novel construction affording substantially improved cleaning efficiency.

Pipe cleaning nozzles provided heretofore are characterized by inefficient cleaning action, requiring excessive time to achieve satisfactory results. Further, they are characterized by creating a back pressure which requires excessive manual effort to overcome the resulting resistance to forward movement of the nozzle through a pipe.

SUMMARY OF THE INVENTION

In its basic concept the nozzle of the present invention provides a plurality of high velocity fluid pressure jets which converge forwardly about a forwardly projecting tip to effect removal of solids from pipes with maximum speed and efficiency. Additional high velocity fluid pressure jets are directed angularly rearward to assist forward movement of the nozzle through a pipe and rearward expulsion of solids removed from the pipe.

It is by virtue of the foregoing basic concept that the principal objective of the present invention is achieved, namely to overcome the disadvantages of prior nozzles, as discussed hereinbefore.

The foregoing and other objects and advantages of the present invention will appear from the following detailed description, taken in connection with the accompanying drawing of the preferred embodiments.

BRIEF DESCRIPTION OF THE DRAWING

FIG. 1 is a foreshortened plan view of a pipe cleaning nozzle embodying the features of the present invention.

FIG. 2 is a front elevation of the nozzle as viewed from the left in FIG. 1.

FIG. 3 is a view in transverse section taken on the line 3-3 in FIG. 1.

FIG. 4 is a view in transverse section taken on the line 4-4 in FIG. 1.

FIG. 5 is a fragmentary view in longitudinal section taken on the line 5-5 in FIG. 2.

FIG. 6 is a fragmentary sectional view taken on the line 6-6 in FIG. 5.

FIG. 7 is a fragmentary view in longitudinal section, similar to FIG. 5, showing a modified form of pipe cleaning nozzle embodying the features of this invention.

FIG. 8 is a view in transverse section taken on the line 8-8 in FIG. 7.

DESCRIPTION OF THE PREFERRED EMBODIMENTS

Referring first to the embodiment illustrated in FIGS. 1-6, the pipe cleaning nozzle includes a hollow body 10 closed at its forward end by an integral transverse wall 12. The internal chamber 14 defined by the body and wall communicates with a source (not shown) of fluid under pressure by such means as an elongated pipe 16. The pipe is coupled to the body by such means as welding, or by the interengaging threads illustrated.

The source of fluid pressure generally is a source of high pressure water. However, it may be any other suitable liquid, air or other gas.

Extending through the front wall 12 of the body are 5 a plurality of peripherally spaced jet ports 18 which communicate at their rearward ends with the chamber 14. There are three such ports in the embodiment illustrated. These ports are disposed with their longitudinal axes 18' converging forwardly of the body. Although 10 these axes may be arranged to intersect at a common point on the longitudinal axis 10' of the body, it is preferred that they be offset angularly with respect to the longitudinal axis of the body (FIGS. 2 and 6) so that they do not intercept the latter axis. It has been found 15 that this arrangement contributes beneficially to the speed and efficiency of removal of solids accumulations within a pipe.

Projecting forwardly from the front end of the body, 20 and formed integral therewith, is a tip 20. Although the tip is illustrated as being of conical shape, it may be cylindrical, triangular, square, or any other shape desired. Further, the tip need not taper forwardly, as illustrated, the only requirement being that it not intercept the 25 converging axes 18' of the jet ports 18.

In the embodiment illustrated the conical tip 20 converges forwardly from the outer periphery of the transverse wall 12. An elongated groove 22 is provided in the tip in registry with each of the jet ports 18. These 30 grooves provide unobstructed channels for the high velocity fluid pressure jets emitted from the ports 18.

In the preferred embodiment illustrated, there is also 35 provided a plurality of peripherally spaced fluid pressure jet ports 24 which communicate at their inner ends with the chamber 14 and which extend outwardly through the body angularly rearward with respect to the body. These ports provide rearwardly directed jets of high velocity fluid under pressure. These jets perform a dual function. First, they provide a thrust in the 40 direction assisting forward movement of the nozzle through a pipe being cleaned, thereby materially reducing the manual effort required to move the nozzle forwardly through the pipe. Second, they accelerate the flow of fluid rearwardly through the pipe to assist the 45 removal of dislodged solids from the pipe.

In the embodiment illustrated there is also provided 50 a plurality of peripherally spaced fluid pressure jet ports 26 which communicate at their inner ends with the chamber 14 and which diverge outwardly through the front wall 12 of the body. These ports provide high velocity jets of fluid under pressure which are directed angularly forward to impinge upon the inner surface of the pipe being cleaned, to assist the fluid pressure jets through the converging ports 18. If desired, these forwardly diverging ports 26 may be omitted.

In the embodiment illustrated in FIGS. 1-6 the tip 20 is made integral with the body 10. In the embodiment illustrated in FIGS. 7 and 8 the tip is provided as a separate element adapted to be secured removably to the body. To this end the rearward portion of the tip is provided with a non-circular stem 28 arranged for removable reception in a correspondingly non-circular opening through the front wall 12 of the body. An internally threaded bore in the stem receives the threaded shank 30 of an attaching screw. The head 32 of the screw overlaps the adjacent portion of the inner surface of the front wall 12, for securing the tip firmly to the body. A 60 65

gasket 34 is interposed between the screw head and front wall to provide a fluid tight seal.

The non-circular stem 28 and opening serve to orient the tip rotationally so that the grooves 22 register properly with the jet ports 18, as will be understood. If the configuration of the tip is such that its entire periphery is confined within the axes 18' of the ports 18, a circular stem and opening may be utilized.

The nozzle of the present invention functions effectively to clean pipes with maximum speed and facility. In this regard the term "pipe" as employed herein and in the appended claims is intended to include all types and varieties of pipes, tubings and conduits from which it is desired to remove solids accumulations resulting from simple plugging by debris, water hardness accumulations, chemical corrosion accumulations and many other factors.

In use, the nozzle is connected to a source of fluid under high pressure, as by means of a long pipe 16. With fluid under pressure being ejected through the ports as high velocity jets, the tip end of the nozzle is inserted into the pipe to be cleaned. The forwardly converging jets emitted from ports 18 function to break loose the solids accumulations forwardly of the tip 20 in a radially expanding manner. Although the tip may be employed as a ram or chisel in breaking up the solids, it has been found in most instances that maximum disruption of solids is achieved by the action of the converging jets. Thus, the tip serves primarily as a depth gauge by which to properly position the converging jets. In this regard the operator moves the nozzle forward in the pipe until the tip engages the solids accumulation, and then retracts the nozzle a distance predetermined to position the converging jets for optimum action.

The forwardly diverging jets from the ports 26 assist the converging jets from the ports 18 in breaking up the solids and removing the last traces from the inner surface of the pipe. The ejected fluid from these ports entrain the solids and flows rearward through the pipe. This rearward flow of fluid is enhanced by the jets emitted from the rearwardly directed ports 24. In addition, the jets from these ports provide a forward thrust to the nozzle, thereby minimizing the manual effort required for moving the nozzle forwardly through the pipe.

To illustrate the effectiveness of the nozzle of the present invention, it has been found by comparative tests with nozzles of the prior art that more thorough cleaning of a given length of substantially identically plugged pipes is achieved with the nozzle of the present invention in about one-fifth to about one-tenth the time required with nozzles of the prior art, and with significantly less manual effort on the part of the operator.

It will be apparent to those skilled in the art that various changes may be made in the size, shape, number and arrangement of parts described hereinbefore. For

example, it has been explained hereinbefore that the axes 18' of the jet ports 18 may be arranged to converge to a common point on the longitudinal axis 10' of the nozzle body, forwardly of the tip 20. The illustrated offset arrangement of these axes is preferred, since the spiral action of the jets has a greater disruptive effect on the solids accumulation in the pipe. In similar manner, the jet ports 24 and 26 may be directed radially outward through the body, rather than angularly as illustrated in FIGS. 3 and 4. The arrangement illustrated is preferred since it provides a spiral motion to the jets to enhance removal and expulsion of solids from the pipe. The number of jet ports may be varied, as desired, as will be understood. The foregoing and other changes may be made without departing from the spirit of this invention.

Having now described my invention and the manner in which it may be used, I claim:

1. A pipe cleaning nozzle comprising
  - a body having an external cross section smaller than the internal cross section of a pipe to be cleaned, for movement of said body freely through said pipe to be cleaned,
  - the body having a front wall and an internal chamber adapted to be coupled, independently of the pipe to be cleaned, through an elongated supply pipe to a source of fluid under pressure,
  - a tip on the front wall of the body projecting forwardly therefrom, and
  - a plurality of peripherally spaced fluid pressure jet ports through the front wall of the body communicating at their inner ends with the chamber and arranged on forwardly converging axes which are disposed outwardly of the tip and which may intersect each other only forwardly of it, for providing unobstructed convergence of high velocity jets of said source fluid forwardly of the tip.
2. The pipe cleaning nozzle of claim 1 wherein the jet ports converge forwardly on axes offset angularly with respect to the longitudinal axis of the body so as not to intercept said latter axis.
3. The pipe cleaning nozzle of claim 1 including a plurality of peripherally spaced fluid pressure jet ports through the body communicating at their inner ends with the chamber and arranged on axes extending angularly outward in the rearward direction of the body, for directing high velocity jets of said source fluid rearwardly relative to the body simultaneously with said forwardly converging jets, to assist forward movement of the body through the pipe to be cleaned and to accelerate the flow of said source fluid rearwardly through the pipe to be cleaned for assisting rearward removal of dislodged solids from said pipe.
